UNITED STATES PATENT OFFICE.

MAX AMS, OF NEW YORK, N. Y.

SHEET-METAL CAN.

SPECIFICATION forming part of Letters Patent No. 593,558, dated November 16, 1897.

Application filed April 1, 1897. Serial No. 630,273. (No model.)

To all whom it may concern:

Be it known that I, MAX AMS, of New York city, county and State of New York, have invented an Improved Sheet-Metal Can, of 5 which the following is a specification.

This invention relates to a sheet-metal can united at its overlapping edges without solder and in such a manner as to effectively withstand pressure.

10 Owing to sanitary considerations it is very desirable that sheet-metal preserve-cans should contain no solder in the joint; but as these cans are subjected to a severe interior steam-pressure the difficulty arises to construct a joint free from solder which will not open under this pressure. By my invention 15 such a joint is formed in a simple, strong, and workmanlike manner.

In the accompanying drawings, Figure 1 is 20 a perspective view of my improved sheet-metal can; Fig. 2, a cross-section through the joint, showing it open for the sake of greater clearness and before being corrugated; Fig. 3, a longitudinal section on line 3 3, Fig. 2; and 25 Fig. 4 is a longitudinal section on line 4 4, Fig. 1.

The letter *a* represents the plain cylindrical body of a sheet-metal can, which is closed along its upright edge by a lap-joint *a'*, into which a suitable packing *b* is introduced.

30 After the lap-joint has been formed the overlapping sections of the metal are subjected to the action of a pair of dies, which will corrugate, crimp, or bulge the metal, Fig. 4. These corrugations, crimps, or bulges are

formed in all the four thicknesses of the joint, 35 and in this way the parts of the joint are so interlocked that the projections of any one thickness are received by corresponding depressions of the adjoining thicknesses. The corrugations *a* extend transversely across the 40 joint and from edge to edge thereof, but not into the body of the can. I prefer to form the corrugations at an inclination to the bottom of the can, whereby the resistance against radially-acting interior pressure is increased. 45

It will be seen that by the construction described a reliable joint is formed, which is perfectly tight and will effectively withstand steam-pressure.

What I claim is—

1. A sheet-metal can, having its joint or seam provided with a series of inclined transverse corrugations or creases extending from one end of the joint or seam to the other, substantially as described.

2. A sheet-metal can having a joint or seam, composed of four thicknesses of metal, and which joint or seam projects beyond the outer circumference of the can, and is provided with a series of transverse inclined corrugations 60 or creases which extend from one end of the seam or joint to the other, substantially as specified.

MAX AMS.
